UNITED STATES PATENT OFFICE.

WILLIAM F. FRECH, OF BROOKLYN, NEW YORK, ASSIGNOR TO CARY MANUFACTURING CO., OF BROOKLYN, NEW YORK, A CORPORATION OF NEW YORK.

THIMBLE FOR COILED BOX STRAPPING.

Application filed February 21, 1920. Serial No. 360,444.

To all whom it may concern:

Be it known that I, WILLIAM F. FRECH, a citizen of the United States, residing at the city of New York, borough of Brooklyn, county of Kings, and State of New York, have invented a new and useful Thimble for Coiled Box Strapping, of which the following is a specification.

This invention is a thimble for connecting a hanger to the spool of coiled box strapping, the object being to provide a secure and efficient attaching means capable of economical manufacture and easily attachable to the several parts.

According to this invention, the thimble is produced by cutting a blank in one piece from sheet metal, said blank being provided in two of its edges with notches, the bottom edges of which notches are rounded so as to leave well defined margins adapted to perform the function of retaining flanges.

The stamped blank is rolled into the form of a tube, the respective ends of which are indented by the notches. In assembling the parts, the box strapping is coiled upon a spool, and the coil and the attached spool are positioned within the hanger, after which the thimble is thrust through openings provided in the spool and the hanger, and finally the notched end portions of said thimble are bent outwardly, i. e., the members formed by the notches and the marginal portions of the metal intermediate said notches are turned over so as to have frictional contact with the hanger and a firm bearing thereon, whereby the side portions of the hanger are retained in close engagement with the spool and the thimble is so firmly attached to the hanger so as to preclude separation of the parts under the comparatively rough usage to which the strapping is subjected while undergoing transportation or in service.

The invention in a practical form is illustrated in the accompanying drawing, wherein—

Figure 1 is a side elevation of the reel, hanger and attaching thimble.

Figure 2 is a cross section on the line 2—2— of Figure 1.

Figure 3 is a perspective view of the thimble on an enlarged scale and detached from the reel.

Figure 4 is a plan view of the stamped steel metal blank.

The salient feature of this invention is the thimble A, shown in Figure 3, produced from the stamped metal blank, B of Figure 4. Said blank is substantially rectangular, and it is provided in two of its edges with two series of notches b, b', one series in each edge, the edges of the metal blank intermediate the notches being rounded or curved at c. The thimble is produced by rolling the stamped notched blank into tubular form as shown in Figure 3, the end portions of said thimble being indented by the notches.

C is a spool, composed usually of soft material such as wood, fibre or the like, and D is a thin metal strap, known usually as box strapping for the reason that it is used for binding a shipping package, such as a box or crate, to which the strapping is nailed or otherwise applied. The metal strap is coiled upon the spool, and the attached coil and spool are mounted within a hanger E by the thimble A, said hanger being composed usually of a metal strap doubled to produce a loop the side members of which lie in close relation to the faces of the spool and the edges of the coiled strapping, see Figure 2. The spool is centrally apertured, at d, and the side members of the hanger are provided with apertures e, the latter being in register with the spool aperture d, when the parts are assembled by positioning the spool and the coil between the side members of the hanger.

The thimble constitutes the means for connecting the spool to the hanger and as a journal upon which the spool and reel are free to turn in drawing the strapping off the coil. Said thimble is passed through the aligned apertures in the spool and the hanger, the thimble being sufficiently long for the notched end portions to protrude beyond the side members of said hanger.

It will be noted that the notches produce tongues f, f', at the opposite end portions of the thimble, and in placing the thimble in position these tongues and the curved margins c pass beyond the outer faces of the hanger, whereby the tongues are adapted to be bent outwardly as shown in Figures 1 and 2, and the margins c of the thimble are also bent outwardly to produce narrow flanges, shown more clearly in Figure 2. The tongues f, f', are sufficiently long to have engagement with the outer faces of hanger on the side members thereof, but by the

flanging the curved edges *c* of the thimble the side members of the hanger are drawn into close contact with the respective faces of the spool and with the edges of the coiled 5 strapping. The described construction provides for the secure attachment of the thimble to the hanger so that there is very little possibility of the thimble becoming detached from said hanger, the thimble 10 forming the function of a journal on which the spool and the coil are free to rotate when the operator pulls the box strapping off the coil.

It will be understood that the thimble can 15 be produced rapidly and cheaply for the reason it is only necessary to stamp the blank out of sheet metal and bend said blank into tubular form. The thimble is assembled with the spool, coil and hanger 20 quite easily, and the tongues and flanges are bent by appropriate tools so as to permanently attach said thimble to the hanger.

Having thus described the invention, what 25 I claim as new is;—

1. The combination with a hanger, of a thimble provided at its respective end por-

tions with alternate notches and tongues, the notched end portions of said thimble being inserted through opposite members of said hanger and the tongues being bent into contact with said hanger members, and a spool 30 rotatably mounted on the thimble, the margins of the thimble intermediate said tongues being upset for drawing the members of the hanger into contact with the end faces of 35 the spool.

2. A thimble adapted to serve as a means for rotatably mounting a coil-carrying spool within a hanger, composed of a metal blank 40 provided with notches the inner margins of which are curved, said metal blank being bent into tubular form and the notched portions of which are bendable into contact with the hanger, said curved margins of the thimble at the inner ends of the notches being 45 bendable to produce flanges whereby said flanges and the bent end of the thimble operate to draw the hanger into contact with the spool.

In testimony whereof I have signed my 50 name hereto this 13th day of February, 1920.

WILLIAM F. FRECH.
